(57) **CLAIM**

The ornamental design for a toy for a pet, as shown and described.

DESCRIPTION

FIG. 1 is an enlarged front perspective view of a toy for a pet showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is a blank based on the inside FIG. 1; and,

FIG. 9 is a blank based on the outside of FIG. 1.

The broken lines in FIG. 1 are for illustration only and form no part of the claimed design.

1 Claim, 3 Drawing Sheets Fig. 1.

Fig. 2.

Fig. 3.

Fig. 4.

Fig. 5.

Fig. 6.

Fig. 7.

Fig. 8.

Fig. 9.
